Des. 215,845

Patented Nov. 4, 1969

215,845

VAPORIZER BOWL OR THE LIKE

Lawrence Katzman, New York, Edward Briggan, New York County, and Monte L. Levin, Kings County, N.Y., assignors to Kaz Manufacturing Co., Inc., New York, N.Y., a corporation of New York

Filed Jan. 21, 1969, Ser. No. 15,423

Term of patent 14 years

Int. Cl. D23—04

U.S. Cl. D23—148

FIG. 1

FIG. 2

FIG. 3

FIG. 4

FIG. 1 is a front elevational view of a vaporizer bowl or the like embodying our new design;

FIG. 2 is a top plan view thereof;

FIG. 3 is a side elevational view, partly in section, the other side being identical; and

FIG. 4 is a bottom plan view thereof.

We claim:

The ornamental design for a vaporizer bowl or the like, as shown and described.
